UNITED STATES PATENT OFFICE.

VIRGIE E. BRATTON, OF NEWARK, OHIO.

TIMER.

Application filed February 25, 1925. Serial No. 11,603.

This invention relates to improvements in timers used in connection with internal combustion engines.

An important object of the invention is to provide a timer having means associated therewith for supporting and retaining in alignment the timer shaft.

A further object of the invention is the provision of a device of the above mentioned character whereby loosening and rattling of the timer shaft will be prevented.

A still further object of the invention is the provision of a timer of this character which is very durable in construction, simple and efficient for the purpose intended.

Other objects and advantages of this invention will be apparent during the course of the following description.

In the accompanying drawings forming a part of this specification and in which like numerals are employed to designate like parts throughout the same:

Figure 1 is a partial front elevation of an internal combustion engine showing my device associated therewith,

Figure 2 is a vertical sectional view through my improved timer,

Figure 3 is an enlarged sectional view of an adjusting element used in connection with my improved device,

Figure 4 is a perspective view of a portion of the same, and

Figure 5 is a perspective view of the retaining clamp.

In the drawings, wherein for the purpose of illustration is shown the preferred embodiment of my invention, the numeral 10 generally indicates a portion of an internal combustion engine having formed on one side thereof the usual breather pipe 11. As clearly shown in Figure 2 the timer shaft 12 extends forwardly through the engine block and carries a contacting roller 13. This roller is pivotally mounted in association with the timer shaft and retained under tension by means of a coiled spring 14. The roller 13 is adapted to rotate in engagement with an annular ring 15 formed in the timer casing 16, providing means for the "make and break" in the primary circuit by the contact points on this ring. The contact points formed in the annular ring connect with suitable binding posts 17 which extend through the casing and are connected with the conducting wires 18.

The timer casing consists generally of a

cylindrical body 19 having one end enclosed by a substantially frusto-conical projection 20. An internally threaded opening is formed in this projection for receiving an oil cup 21 to permit lubrication of the timing mechanism. The upper portion of the casing carries a U-shaped bracket 22 provided with aligned openings 23 permitting connection of an actuating rod 24. The timer casing is retained in an annular recess 25 formed in the forward extremity of the engine block by means of a suitable retaining clamp which contacts with the extremity of the casing and is secured by means of a bolt 26 threadedly mounted in the upper extremity of the breather pipe 11.

The timer casing 16 is actuated through the medium of the rod 24 and suitable operating mechanism connecting with a spark lever mounted on the steering wheel of the vehicle, thereby advancing or retarding the spark relative to the operation of the engine.

The foregoing description has dealt generally with the usual construction of a conventional type of internal combustion engine and timing mechanism, particularly used upon the well known Ford type of automobile. Referring now more particularly to the structure comprising my invention, I consider it advisable to employ a timer casing which may be of similar configuration to the conventional type ordinarily used upon this type of engine, differing only in the provision of a substantially heavier center piece 27 forming a durable collar provided in the center thereof with a screw threaded opening 28 an externally threaded bolt 29 is adapted to threadedly engage the opening 28 and extends substantially into the casing, the outer extremity thereof being machined to provide a flat projecting tongue 30 operable by means of a wrench or by the fingers. The inner extremity of the bolt 29 is recessed to form a socket adapted to retain therein a ball bearing 31. The outer portion of the bolt 29 adjacent the casing carries a lock nut 32 adapted to retain the bolt 29 in adjusted position.

The usual casing retaining clamp 32' is replaced by an offset clamp 33 of substantially heavier construction provided at one extremity with an opening adapted to engage the bolt 29 and at the other extremity with a slot 34 adapted to engage the breather bolt and be retained in position thereby. The conventional clamp 32' usually em-

ployed in connection with timers of this character may be utilized as a wire guide to prevent the conducting wires 18 becoming entangled with the cooling fan, as plainly shown in Figure 1.

In operation, my improved timer is mounted in much the same manner as the type now commonly employed after which the bolt 29 is adjusted until the ball bearing 31 carried by the inner extremity is in contact with a suitable recess formed on the extremity of the timer shaft. This adjustment is preferably made by hand to prevent the connection being made too tightly.

The ball bearing mounted on the extremity of the said bolt will eliminate any appreciable frictional contact but will be sufficient to retain the timer shaft in alignment. It is well known by those familiar with this art that after appreciable usage the timer shaft becomes loose on its bearings and causes an undesirable rattling in the timer. In addition to this the uneven rotation of the timer shaft prevents proper timing of the motor and material wear of the parts. These undesirable features are eliminated by my improved timer construction.

It is to be understood that the form of my invention herewith shown and described is to be taken as the preferred example of the same, and that various changes as to the shape, size and arrangement of parts may be resorted to without departing from the spirit of the invention or the scope of the subjoined claims.

Having thus described my invention, I claim:

1. A device of the character described including a casing, a bolt threadedly mounted on one extremity of the casing, anti-friction means mounted in one extremity of the bolt adapted to contact with one extremity of the timer shaft, means for locking the said bolt in position, and means for retaining the said casing and bolt in position on an internal combustion engine.

2. In combination with a timing mechanism of an internal combustion engine comprising a rotatable timing shaft, contacting means carried by the said shaft, and an annular recess formed on the engine block, of a casing adapted to engage the annular recess,

a collar having a screw threaded opening formed on the said casing, a bolt threadedly mounted through the said collar opening, 55 an anti-friction bearing formed on the inner extremity of the said bolt adapted to contact with the said timing shaft, means for adjusting the said bolt formed on the opposite extremity thereof, a lock nut carried by 60 the bolt for locking same in adjusted position, and a clamp member adapted to retain the said casing in association with the internal combustion engine.

3. In combination with a timing mechanism including a timing shaft, contact means secured to and rotatable with the shaft, and a casing positioned about the shaft also carrying contacts; a screw threaded bolt 70 threadedly mounted in the center of the casing in alignment with and adapted to contact with the outer end of the shaft, anti-friction means mounted in the end of the bolt to reduce the frictional contact of the bolt and shaft, and locking means engageable with the outer end of the bolt for locking the same in set position so as to retain the shaft in true alignment.

4. In combination with a timing mechanism including a timing shaft, contact means fixed to and rotatable with the shaft, and a casing positioned about the shaft; of means for retaining the timing shaft in alignment including a bolt firmly secured to the casing and engageable with the outer end of the timing shaft, and anti-friction means mounted in the contacting end of the bolt to reduce the frictional contact of the bolt and shaft.

5. In combination with a timing mechanism including a rotary timing shaft, contact means carried by the shaft, and a casing positioned over the shaft; of means for retaining the timing shaft in true alignment including a bolt firmly secured to the casing, anti-friction means mounted in the inner contacting end of the bolt, the said anti-friction means being engageable with a recess formed in the contacting end of the timing shaft, and means for longitudinally adjusting the said bolt.

In testimony whereof I affix my signature.

VIRGIE E. BRATTON.
